Primary Examiner—Brian N. Vinson
Attorney, Agent, or Firm—Wood, Herron & Evans, LLP[57] **CLAIM**

The ornamental design for a portion of a base for a baby diaper changing station, as shown and described.

DESCRIPTION

FIG. 1 is a perspective view of a portion of a base for a baby diaper changing station with a platform in an opened position on a wall and incorporating the new design of the invention, shown in full lines, with the broken lines illustrating the environment of the design;

FIG. 2 is a front view thereof;

FIG. 3 is a left side view thereof with the right side view being a mirror image of FIG. 3;

FIG. 4 is a rear view thereof;

FIG. 5 is a top view thereof;

FIG. 6 is a bottom view thereof; and,

FIG. 7 is a cross-sectional view thereof taken along lines 7—7 of FIG. 2.
